ANTIRATTLER

Francis K. Flynn, Brooklyn, N. Y.

Application June 26, 1942, Serial No. 448,645

1 Claim. (Cl. 292—288)

This invention relates to an anti-rattler for windows, doors or the like.

It is primarily aimed to provide an exceedingly simple construction which may be used in the crack between window and window frame, door and door frame and the like, regardless of the width of the crack, within reasonable limits, thus avoiding the necessity of providing as is necessary under present conditions wedges which must be of a great variety of thicknesses and shapes to fit the various widths of cracks which are encountered, and I further aim to provide such a construction which will avoid the necessity of wedging an anti-rattler in place and one which will not be displaced through wind vibration.

The more specific objects and advantages will in part be pointed out and otherwise become apparent from the description following taken in connection with accompanying drawing illustrating an exceedingly simple, effective and durable embodiment.

In said drawing—

Figure 1 is a view showing the invention in plan and as applied in the crack between a window and window frame, the latter being shown fragmentarily and in horizontal section;

Figure 2 is a plan view of the anti-rattler detached and in normal condition;

Figure 3 is an end elevation of the anti-rattler looking from the handle end; and

Figure 4 is an edge elevation of the anti-rattler.

Referring specifically to the drawing wherein like reference characters designate like or similar parts, the anti-rattler is shown at 10 and is adapted to be made from a single piece or strip of resilient material, for instance spring steel, brass, other metals and plastics. One terminal of the anti-rattler or strip is preferably serrated as at 11 while the other terminal adjacent thereto is preferably sharpened and extends angularly therefrom at 12. Adjacent these terminals, the strip is in contact at 13 and above the zone of contact the strip is formed into a relatively large open loop or handle 14.

The anti-rattler is used in preventing rattling

or vibration under wind or other conditions, between a window 15 and its frame 16 in which it slides, it being understood that the parts 15 and 16 are shown by way of example only since the invention is equally applicable to doors and other closures. The terminal 12 is adapted to be disposed in the crack 17 between the window 15 and frame 16. With my invention, the same is applicable in connection with cracks 17 of various widths. In applying the anti-rattler, the handle 14 is grasped and squeezed or manipulated, relatively moving the parts thereof in contact at 13 until the terminal 12 is sufficiently close to the teeth 11 to enable insertion of the terminal 12 into the crack 17 by lateral sliding movement so that it will occupy the position of Figure 1. When so positioned, the handle or loop 14 is released and the tension of such handle or of the anti-rattler as a whole will depress the teeth 11 into the frame 15 while moving the terminal 12 away from such sash 15. It will be realized that the device is gripped and operated somewhat in the same manner as a pistol.

Various changes may be resorted to provided they fall within the spirit and scope of the invention.

I claim as my invention:

An anti-rattler comprising a resilient strip having approximately straight contacting relatively longitudinally slidably first and second portions, said portions having disaligned terminals so that one of them may enter a crack and the other may engage an adjacent closure, the terminals of said first mentioned portion being angularly disposed with respect to the other terminal, said other terminal being toothed, and a loop connecting said portions, extending immediately from the first mentioned portion and disposed on the opposite side thereof to said angular terminal and then being returned to the other portion to function as a handle and to place one portion in tension for longitudinal sliding movement to separate the terminals when applied.
